The ornamental design for a package for light emitting diode (LED) lighting, as shown and described.

DESCRIPTION

FIG. 1 is a top perspective view of a package for light emitting diode (LED) lighting showing our design;

FIG. 2 is a top plan view thereof;

FIG. 3 is a first side view thereof, the opposing side being a mirror image of that shown;

FIG. 4 is a second side view thereof, the opposing side being a mirror image of that shown;

FIG. 5 is a bottom plan view thereof opposite the view of FIG. 2;

FIG. 6 is a first side view thereof, the opposing side being a mirror image of that shown;

FIG. 7 is a second side view thereof, the opposing side being a mirror image of that shown; and,

FIG. 8 is a bottom perspective view thereof.

Broken lines immediately adjacent to the shaded areas represent the boundaries of the claimed design. Other broken lines are for illustrative purpose only and form no part of the claimed design. None of the broken lines form part of the claimed design.
